HANK FORMING MACHINE AND METHOD

James E. Kerrigan, Arlington Heights, and Raimonds Griekis, Chicago, Ill., assignors to Chicago Printed String Co., Chicago, Ill., a corporation of Delaware

Filed Oct. 2, 1961, Ser. No. 142,422
20 Claims. (Cl. 223—46)

This invention relates to the forming of hanks of ribbon particularly adapted for forming decorative bows. More particularly, this invention pertains to a new and novel method for efficiently forming a hank of ribbon designed to form a decorative bow and to new and novel machines for forming such hanks.

In the commercial sales field, there is an apparently growing practice of packaging various items with embellishments, such as bows, previously associated only with individual gift wrapped packages. Also, many department stores, novelty stores and similar sales organizations make a practice of wrapping gifts in a very decorative manner, often utilizing fancy and individualistic bows formed from ribbon or similar materials. In addition, there is an increasing practice on the part of many individuals of adorning gift packages with pre-formed decorative bows. In each of these areas, the desire is to utilize a bow which has a finished, sophisticated and individualistic appearance such as has usually been associated with bows manually formed by persons having particular skill in preparing such decorative items. However, the manual forming of bows by skilled personnel is of course quite expensive and impractical if attempting to meet a large market demand, i.e. in the nature of several million bows per year. Consequently, a requirement has arisen for methods and machines adapted for efficiently and inexpensively producing decorative bows. Further, particularly in the supplying of large volumes of similar bows for producer or distributor packaging of entire lines of items such as candy, bottled spirits, and the like, it is necessary to provide machines capable of high volume production of such bows.

An illustration of a recently developed bow designed to serve at least a segment of the present and prospective market as outlined above is the bow disclosed in co-pending patent application Serial No. 61,641 of T. Paar. This bow is formed from a hank of ribbon which is secured to a base member with two opposite side portions of the hank in generally parallel side-by-side relation and with the connecting portions of the hank forming conoidal loops. A bow is formed from this hank by unnetting the individual ribbon layers of the end loops to form a pleasing symmetrical bow having several individual aligned conoidal loops or "petals." The present invention is directed to a method and machines for efficiently, and economically producing hanks for such bows and is further directed to providing a method and machines for producing such hanks on a large volume basis. For purposes of clarity and simplicity only, the invention will be described and explained in terms of the formation of hanks of the type described above, however it is intended to encompass such other variations as will occur to those skilled in this art in light of the teachings herein.

It is therefore an object of this invention to provide a method and machines for forming hanks adapted to form decorative bows as outlined above.

It is another object of this invention to provide a simple and expeditious method for forming hanks of ribbon particularly adapted for forming decorative bows.

It is another object of this invention to provide a method for forming hanks of ribbon designed for forming decorative bows and which method is particularly adapted for expedient embodiment in apparatus for mechanically carrying out the method.

2

It is another object of this invention to provide a simple, economical and expedient method for forming a hank of ribbon having opposed portions of the hank disposed in generally parallel coplanar relation.

It is another object of this invention to provide an improved machine for mechanically forming hanks of ribbon.

It is another object of this invention to provide an improved machine for producing hanks of the aforesaid type with a minimum of manual labor or personal attention to the operation of the machine.

It is another object of this invention to provide an improved hank forming machine for mechanized, high volume production of ribbon hanks particularly designed for forming decorative bows.

It is another object of this invention to provide an improved machine for mechanically forming a coil of strip material and applying a base member to such coil in a manner whereby a hank having generally parallel coplanar side portions may be efficiently and economically produced.

These and other objects of this invention will become apparent to those skilled in this art upon a study of the following description, the drawings and the appended claims.

In carrying out this invention in one illustrative form, a hank forming machine is provided which includes means for winding a predetermined length of ribbon into a composite coil of several coextensive contiguous layers, support means for maintaining opposite portions of the coil in spaced relation to one another, mechanism for placing a base member on the coil with portions of the base member adjacent the noted opposite side portions of the coil, and securing means for applying securing devices to independently secure the base member to each such opposite portion, whereby a ribbon hank is formed having two generally conoidal loop end portions and two opposite portions joining the looped end portions, the opposite portions normally being in generally coplanar parallel side-by-side relation.

For a more complete understanding of this invention, reference should now be had to the following discussion and to the exemplary embodiments illustrated in the drawings wherein:

FIG. 1 is a general perspective view, omitting some details, of a hank forming machine employing the teachings of this invention;

FIG. 2 is a top plan view, on a larger scale, of the machine in FIG. 1;

FIG. 3 is an enlarged side elevation view of the ribbon feeding, metering and winding mechanism taken substantially along the lines 3—3 of FIG. 2 and looking in the direction of the arrows but with the cover of the winding chamber in closed position;

FIG. 4 is an enlarged elevation view, partially in section, of part of the coil winding and collapsing mechanism of the machine illustrated in FIG. 1;

FIG. 5 is an enlarged top plan view of the ribbon winding housing and part of the related support and drive mechanism of the machine illustrated in FIG. 1;

FIG. 6 is an enlarged sectional view, taken substantially along line 6—6 of FIGS. 4 and 5 and looking in the direction of the arrows;

FIG. 7 is an enlarged partial side elevation view of the turret, ribbon coil supporting devices and stapling means of the machine illustrated in FIG. 1, but with two of the ribbon coil supporting devices omitted for clarity;

FIG. 8 is an enlarged top plan view of one of the ribbon coil supporting devices of the machine in FIG. 1;

FIG. 9 is a side elevation view taken substantially along line 9—9 of FIG. 8 and looking in the direction of the arrows;

FIG. 10 is an enlarged rear elevation view of the loop sizing mechanism taken substantially along line 10—10 of FIG. 2 and looking in the direction of the arrows;

FIG. 11 is an enlarged side elevation view of the base strip applying mechanism of the machine in FIG. 1, and also illustrates the applier mechanism as extended to engage one of the ribbon coil support mechanisms on the turret;

FIG. 12 is a partial vertical cross section view of the mechanism in FIG. 11 taken substantially along line 12—12 of FIG. 2 and looking in the direction of the arrows;

FIG. 13 is a side elevation view of the opposite side of the mechanism in FIG. 11, and includes the mechanism of FIG. 10;

FIGS. 14 through 21 illustrate various steps in a method of forming and discharging a ribbon hank as carried out with the machine of FIG. 1, with FIG. 21 illustrating an alternative discharge mechanism; and

FIG. 22 illustrates a hank resulting from the method of formation illustrated in FIGS. 14-20, in the process of being formed into a bow by unnesting the end loops.

Referring now to FIG. 1, the major components of the ribbon and ribbon loop manipulative mechanism are shown in general form to illustrate the general arrangement of this machine but with some details omitted. In outline, a ribbon metering feed mechanism 30 directs pre-determined lengths of ribbon into a ribbon winding housing 31 to form a multilayer coil of ribbon. A rotatable turret 32 carries four ribbon coil gripping devices 33 to four predetermined operating positions for carrying out the various operations and forming a hank. Referring now also to FIG. 2, these four positions will be referred to herein as positions I, II, III and IV starting at the winding housing and moving clockwise. A ribbon coil sizing apparatus 34 and a base strip applying mechanism 35 are positioned adjacent to position II. Two opposing stapling mechanisms 161 and 162 are disposed one above and one below the plane in which a ribbon coil is supported by the ribbon coil gripping mechanism in position III. A suitable hank discharge mechanism is provided at position IV for discharging the formed hanks into a suitable receptacle (not shown). Suitable drive and control means for operating the various disclosed elements may be provided beneath the framework and within the housings illustrated in FIG. 1.

Referring now more specifically to FIGS. 1, 2 and 3, the ribbon feed mechanism 30 which withdraws ribbon 44 from an indeterminate length supply, such as the spool 39 illustrated in FIG. 1, and intermittently feeds pre-determined lengths of this ribbon into the winding housing 31 includes a pair of supply rollers 40 and 41 and a pair of metering feed rollers 42 and 43. The supply rollers 40 and 41 withdraw ribbon 44 from the spool 39 to maintain a loose supply of ribbon in reservoir 45. Rollers 40 and 41 may be driven from any suitable power source through a variable speed or start-stop drive connection. Feed roller 42 is constantly driven by a suitable power source such as motor 46 through drive belt 46a. Roller 43 is an idler and is mounted on rocker arm 47 which is pivoted at 47a for selective movement of the roller into and out of engagement with ribbon 44 passing between rollers 42 and 43 to effect intermittent feed of the ribbon between the feed rollers and through a slot 48 in guide plate 48a to the winding housing 31.

The feeding operation is controlled through a suitable feed timing mechanism 49 which operates a feed control hydraulic valve 50. The feed cycle is started by an impulse switch 51 actuated by a bell crank 52 in response to movement of the ribbon coil collapsing fingers 70 and 71, to be later described. Appropriate movement of the bell crank 52 actuates impulse switch 51 which in turn trips timer 49 to actuate valve 50. Valve 50 passes fluid to a hydraulic cylinder 53 which thereby rotates arm 47 in a clockwise direction (as viewed in FIG. 3) and urges

roller 43 against the ribbon 44 and the ribbon against roller 42. The ribbon 44 is thus clamped between driven roller 42 and idler roller 43 whereby the rollers feed the ribbon into the winding housing 31. During the feeding movement, roller 43 is rotated under the influence of roller 42 in direct proportion to the length of ribbon passing between the rollers. The idler roller 43 is drive-connected to the timer 49, as through a timing belt (not shown). Timer 49 permits a predetermined amount of rotation of roller 43 then trips valve 50 which deactivates cylinder 53 to permit counterclockwise rotation of rocker arm 47 whereby idler roller 43 moves away from driven roller 42 and the feed of the ribbon is stopped. As idler roller 43 moves downward, it engages a brake member 55 which is biased upwardly by springs 56 to stop roller 43 and prevent overrun in the feed of the ribbon. The feed mechanism is then in position to be recycled to feed the next successive predetermined length of ribbon upon being actuated through suitable movement of the bell crank 52 as aforescribed.

In the illustrated machine, a variable speed transmission 57 is driven from belt 46a and is suitably drive connected to roller 41. The speed ratio of the transmission, and hence the speed of rollers 40 and 41 and the rate of feed of ribbon to reservoir 45, is controlled through a suitable control lever 58 positionable against an adjustable stop 58a. Lever 58b is connected to suitable mounting means for moving roller 40 away from roller 41 for stopping the feed of the ribbon to the reservoir.

A movable cutting bar 59 is moved in proper sequence, as by a suitably controlled hydraulic cylinder 60, and cooperates with the exposed end of plate 48a to cut the ribbon at the outlet end of slot 48 after each ribbon feeding cycle.

Referring now additionally to FIGS. 4 and 5, the illustrated ribbon winding housing 31 constitutes a hollow cylindrical housing defined by a plate 61, a curved wall portion 62 adjustably fixed to plate 61, a movably mounted wall portion 63 which complements fixed wall portion 62, and a pivotally mounted removable cover or end plate 64 which is positionable to close the cylindrical housing. Movable wall segment 63 is fixed to an arm 65 which is pivotally mounted as at 66 and biased to movement in a clockwise direction (as viewed in FIGS. 3 and 4) against an adjustable stop 67 by a tension spring 68. Spring 68 thus normally maintains the movable section 63 in a position defining a closed housing of a predetermined diameter but permits slight yielding movement of this section to increase the effective diameter of the housing under the pressure of certain types of ribbon being coiled in the housing. The complementary curved walls 62 and 63 define a slot as at 69 opposite the outlet end of slot 48 to receive the ribbon which is directed into the housing generally tangentially of the cylindrical housing enclosure. Due to the manner in which the ribbon is supported and directed into the housing, ribbon having suitable body and friction characteristics will spiral along the inner curved wall of the housing and form a multilayer coil therein when an appropriate length of ribbon is forced inward through slot 69. It will be appreciated that as a coil of ribbon is formed, the innermost turns must assume circular shapes of successively lesser diameters if the diameter of the housing is maintained constant, due to the increasing thickness of the ribbon coil. Some ribbon materials which are very smooth and have low coefficients of friction as to both surfaces have been found to automatically adjust to such lesser diameters; one such ribbon material is a decorative tying tape product "Satintone" produced and sold by Chicago Printed String Company of Chicago, Illinois. Other ribbons, such as laminated tapes having a higher coefficient of friction as to one or both surfaces have been found not to adjust as readily to the lesser diameters as the coil is formed, hence for such tapes it is necessary to provide one yieldably adjustable side 63 of the housing to permit the housing to expand to success-

sively larger diameters as the coil is formed; an example of the latter type of ribbon materials is the decorative typing tape product "Chiprene" produced and sold by Chicago Printed String Company of Chicago, Illinois.

The winding housing 31 is formed with diametrically opposed slots through the curved sidewalls to receive a pair of coil collapsing fingers 70 and 71. The slot 72 to receive the upper finger 70 is formed between bifurcated segments of one end of the movable curved wall 63 while the corresponding opposite slot to receive the lower finger 71 is formed through the end portions of both curved wall portions 62 and 63. The fingers 70 and 71 are reciprocated inwardly through these slots, subsequent to the formation of a ribbon coil in the housing, to collapse the coil in the manner generally illustrated in FIGS. 14 and 15. A slide plate 73, for supporting and directing the ribbon, retracts when finger 70 is extended downwardly but substantially narrows slot 69 while finger 70 is retracted during the ribbon coiling operation. Plate 73 is moved to and fro between the two positions illustrated in FIG. 4, in proper sequence, by appropriate actuation of a hydraulic cylinder and piston element 75 which includes a piston rod 76 connected to the slide plate.

The winding housing and related mechanism, are supported on a pair of slide rods 77 and 78 which are slidably supported in bushing members 79 and 80 mounted on the machine framework. A mounting block 81 is carried on rods 77 and 78 and in turn supports a support block 82 to which is secured the wall plate 61 of the winding housing. The structure supported on rods 77 and 78 is reciprocated by suitable means such as a hydraulic piston and cylinder element 83 secured at one end to a fixed mounting such as bushing 79 and having a piston rod 84 secured to mounting block 81.

Fingers 70 and 71 are carried by a pair of racks 85 and 86, respectively, slidably mounted in the mounting block 81 and retained therein by cover plates 87 and 88. The racks are reciprocably driven by a pinion 89 mounted on rotatable shaft 90 which is in turn rotatably oscillated by a rack 91 and pinion 92 at its opposite end. Rack 91 may be reciprocably driven by suitable means such as a hydraulic cylinder and piston element 93 mounted on slide rods 77 and 78 through member 93a as illustrated in FIG. 5. Suitable actuation of the element 93 reciprocates rack 91 thereby causing rotary oscillation of shaft 90 and concomitant reciprocation of racks 85 and 86 and fingers 70 and 71.

Cover plate 64 is carried on a shaft 95 which is rotatably mounted in wall plate 61. The shaft 95 is drive connected to shaft 90 through a timing belt 96 and pulleys 97 and 98 mounted on shafts 90 and 95, respectively, and thus is rotatively oscillated in response to movement of shaft 90 to move cover plate 64 between its closed position illustrated in FIG. 3 and its open position illustrated in FIG. 4.

It will be appreciated of course that the winding housing may be adjusted to form coils of ribbon of different diameter such as by adjusting the position of the fixed curved wall 62, through an adjustable mounting as at 99, by adjusting the pivotal mounting point 66 of movable wall 63, and/or by adjusting the stop 67. Alternatively, curved wall portions of different diameters may be substituted. Fingers 70 and 71 may be correspondingly adjusted on racks 85 and 86 by providing adjustable mounting slots as at 100.

Referring now more specifically to FIGS. 2, 7, 8 and 9, the illustrated machine includes four coil gripper mechanisms 33 equally spaced about the periphery of rotatable turret 32. The turret 32 is supported on a vertical drive shaft for rotation by any suitable drive mechanism, such as a four-position Geneva cross gear drive, for moving the gripper mechanisms to the four stations of the machine.

Each of the coil gripper units 33 is supported on the turret 32 on a mounting block 101 and includes an anvil 102 suitably secured to the mounting block and ex-

tending radially outward of the turret 32 in a generally horizontal plane. The upper and lower surfaces of the distal end of the anvil may be formed with staple clinching grooves or detents 103 as indicated. A pair of gripping fingers 104 are pivotally mounted on block 101 above the anvil 102 with resilient grippers 106 opposed to the flat upper surface of anvil 102 at each side of detents 103, adjacent the opposite edges of the anvil. A second pair of gripper fingers 107, each including a resilient gripper 106, are similarly mounted on block 101 beneath anvil 102 generally opposite the fingers 104. Fingers 104 and 107 are normally urged to the closed position, with grippers 106 against the opposite sides of anvil 102, by a linkage and spring mechanism indicated generally at 108. This mechanism may take various forms but as illustrated includes links 109 and 110 pivotally joined to the inward ends of fingers 104 and 107 respectively and pivotally joined to one another and to block 111 by engaging a pivot pin 112. Block 111 is slidably engaged on a pin 113 which is secured to block 101 and extends inwardly therefrom. The block 111, and consequently the joined ends of links 109 and 110, are normally biased to an outward position, wherein fingers 104 and 107 are pivoted to the gripping position illustrated at position III in FIG. 7, by a compression spring 114 confined between block 111 and a nut 115 on the distal end of pin 113. A bell crank lever 116 is pivotally mounted on a pin 117 and is provided with a bifurcated portion 116a at its upper end normally engaging block 111 astraddle pin 113 as illustrated. The opposite end of arm 116 includes an abutment member 118 adapted for engagement by a plunger, such as is indicated at 119, for movement of block 111 against the force of spring 114 and thereby to open the gripper fingers as illustrated in FIG. 9. A plunger such as 119, which may be actuated by a suitable hydraulic cylinder and piston element (not shown), may be provided at each position wherein it is desired to open the gripping fingers. In the illustrated machine such hydraulic elements are appropriately disposed to selectively open the gripper fingers at positions I, II and IV for purposes to be later described.

The anvils or center supports 102 are disposed to be in axial alignment with the winding housing 31 when in position I and when the housing is extended toward the turret. As the illustrated slide rods and hydraulic element move the housing axially, this places the anvils of this machine along an extension of the axis of the housing when in position I. With a coil of ribbon collapsed as in FIG. 15, inward movement of the housing positions the collapsed coil astraddle an anvil 102 and with the opposing upper and lower portions of the coil between the respective open gripper fingers and the anvil, to be gripped upon closing of the fingers, see FIGS. 1 and 16. After the grippers are closed and the housing retracted, the turret drive is cycled to rotate the turret and the gripped coil is carried to position II. The mechanism at position II cooperates with the gripper mechanism to size the coil and to apply a base strip to the collapsed coil.

Referring now more particularly to FIGS. 2 and 10-13, the mechanism illustrated at position II includes a coil sizer 34 and a base strip feeder and applier 35, both of which include parts reciprocable toward and away from a gripping mechanism in position II. A housing 120 serves as a support for the operative mechanism which includes a slidably mounted horizontal plate 121 and attached vertical plate 122 reciprocably driven by a suitable actuating means such as a hydraulic cylinder and piston element 120a.

The sizing mechanism 34 (FIGS. 2, 10 and 13) includes a pair of crank arms 123 and 124 supported at the inward side of plate 122 on shafts 125 which are rotatably mounted in the plate 122. Shafts 125 are op-

eratively joined to a crosshead 126 through arms 127 and links 128. Crosshead 126 is mounted for vertical reciprocating movement by a suitable drive means such as a hydraulic cylinder and piston unit 129 which is also supported on plate 122. Sizing pins 130 protrude inwardly from the distal ends of links 123 and 124 and are movable, on actuation of unit 129, between the positions illustrated in FIG. 10. This actuation takes place while the sizing unit is extended by the hydraulic unit 122 with pins 130 projecting into the opposite end loops of a coil in position II as illustrated in FIG. 17, and serves to size the coil, particularly the innermost turn of ribbon which often tends to be loose and considerably smaller than the superposed turns.

The base strip feeding and applying mechanism 35 illustrated in FIGS. 2 and 11-13 includes a pair of feed rollers 131 and 132 for intermittently extending the free end portion of an indeterminate length of strip material 133 to a position generally between plate 121 and an anvil 102 in position II, see FIG. 11. The strip 133 passes through a guide 134, between rollers 131 and 132, and thence upwardly through slot 135 in plate 136. With reference to FIG. 13, the feed rollers are intermittently actuated by forward movement of plate 121 through a cam plate 137 carried on plate 121, a follower 138 on rocker arm 139, a connecting link 140, a bell crank rocker plate 141 mounted on pivoted shaft 142, a tension spring 143, and a one-way clutch drive (not shown) connected between shaft 142 and one of the rollers 131 and 132. The length of tape fed during each movement of this drive mechanism is controlled by an adjustable stop 144 which limits the rotary return movement of plate 142. Overrun of the tape feed is prevented by providing a brake drum 144a which is drive-connected to the rollers and by providing a brake spring 144b on arm 139 for engaging drum 144a at the end of the work stroke of arm 139.

Plate 121 also carries a pair of presser members 145 and 146 and a resiliently mounted sliding plate 147 carrying a presser shoe 148, see FIGS. 2, 11 and 12. The presser plates are spaced apart approximately the thickness of anvil 102 and are biased toward one another by compression springs 149 on mounting bolts 150 extending through plates 145, 121 and 146. Plate 147 is slidably supported on plate 121 by studs 151 and 152, extending through slot 153 in plate 147 and into plate 121, and is yieldably biased forwardly by tension spring 155 connected between stud 151 and a stud 154 mounted in plate 147. A second cam plate 156 is connected to plate 121 and positioned to urge follower 157 against the abutment portion 158 of shear plate 159 and thus to reciprocate plate 159 and cut the base strip 133 at 160 as plate 121 is moved forward.

In operation, as plate 121 moves forward, the feed rolls are activated to extend the base strip tape as illustrated in FIGS. 11 and 18. Presser foot 148 then engages the extended end of the tape against the end of an anvil 102 under the force of spring 155, and cam 156 actuates the shear plate 159 to cut off the end portion of the tape. Plates 145 and 146 fold the cutoff portion of tape over the ends of grippers 106 and the portion of the ribbon coil therebetween, as indicated generally in FIG. 19 and more particularly in the changed-position portion of FIG. 11. While the tape and coil are thus gripped by plates 145 and 146 and shoe 148, fingers 104 and 107 are opened and permitted to re-close by an activating element, such as a plunger 119, at position II to thereby engage the base strip under the grippers 106. The reciprocable elements of mechanisms 34 and 35 are then retracted and the turret drive is operated to carry the coil and applied base strip to position III.

As illustrated in FIGS. 1, 2, 7 and 20, at position III the gripper mechanisms 33 support the coil of ribbon and the superposed folded base strip between a pair of

7
suitable staplers 161 and 162. These two staplers are positioned in opposition to one another and are each disposed to apply a securing device such as a staple through the portion of the base strip overlying the adjacent side of the ribbon coil and through this adjacent side of the coil to secure the base strip and the corresponding adjacent layers of ribbon together. In this machine this is accomplished by forming a U-shaped staple from a length of wire 163 and forcing the legs of the U through the adjacent portion of the base strip and layers of ribbon and into detents 193 of the anvil which serve to clinch the legs of the staples. Each of the staplers may be of a known conventional type, and actuated by any suitable means controlled with relation to the operation of the remaining portions of the hank forming apparatus.

Subsequent to the stapling operation, the turret drive mechanism is again operated to move the stapled hank from position III to position IV where the hanks are discharged from the machine to a suitable receptacle (not shown). The discharge mechanism 33 may be in the form of a tube and valve for applying a hydraulic blast as indicated in FIG. 1 or may be a suitable kicker mechanism such as the rotatably mounted shaft 164 and protruding fingers 165 illustrated in FIG. 21. Shaft 164 is suitably driven for rotative oscillation between the two positions shown in FIG. 21 for "kicking" the hanks from the grippers in position IV after the fingers 104 and 107 are opened, as by a suitably operated plunger 119 disposed at this position. A similar gripper opening mechanism would also be included with the hydraulic discharge device. The turret drive is now operated to move the empty gripper mechanism to position I to receive another coil.

Operation and Method

The novel method of this invention and the operation of the illustrated machine may be summarized and described with references to FIGS. 14 through 21. A predetermined length of tape 44 is first formed into a coil 166, as illustrated in FIG. 14, by feeding the tape into the hollow cylindrical housing of the winding mechanism and severing the coiled tape from the supply. The fingers 70 and 71 are then extended into the housing to collapse coil 166 into the general form illustrated in FIG. 15. The housing and collapsing fingers are extended, as indicated in FIG. 16, to position the collapsed coil astraddle a support member or anvil and with opposite collapsed sides of the coil beneath gripping fingers 45 disposed opposite each side of the support member. The gripping fingers are then closed against the support member to hold the coil astraddle the support, and the winding mechanism returns to its initial position for forming another coil, whereupon the gripping mechanism moves from position I of FIG. 16 to position II indicated in FIG. 17. At position II the loop sizing mechanism is extended to place pins 130 within the end loops of the coil and the sizing mechanism is then operated to move the fingers outwardly to size the coil as indicated in FIG. 18. Simultaneously the strip of tape from which the base strips are taken is extended adjacent the outer side of the coil. The presser foot and clamping members of the base strip applicator mechanism are then extended and the base strip 167 is cut from the continuous tape 133 and folded about the parallel sides of coil 165 as illustrated in FIG. 19. While the base strip and coil are held by the clamping members, the gripping fingers 104 and 107 are opened and again closed to bring the edges of the base strip beneath these fingers. The presser foot, clamping members and sizing mechanism are then retracted and the clamped coil and base strip, being held as indicated in FIG. 21, are carried to position III. At this position, illustrated in FIG. 20, securing devices are independently applied through each end portion of the base strip and the adjacent portions of the coil, against

anvil 102, whereby the respective end portions of the base strip and the adjacent portions of the coil are independently secured together. The stapled hank is then carried to position IV where it is discharged by a suitable mechanism as indicated in FIG. 21. The result is a hank having generally parallel coplanar side portions disposed in side-by-side relation as indicated in FIG. 22, and from which decorative bows can readily be produced by unnesting the individual ribbon layers of the end loop portions 168.

It will be appreciated that with the illustrated machine each of the aforescribed operations at positions I-IV may be simultaneously performed on successive coils associated with the four gripper mechanisms thereby providing rapid high volume hank production.

The terms "strip material," "tape" and "ribbon" as used herein are not intended to be restrictive phrases, but are intended to include any elongated flexible material which can be manipulated and formed in the general manner described. Two specific examples have been given of suitable decorative strip materials for forming coils for hanks, and it will be apparent that other tapes, ribbons, or the like, having similar characteristics may also be utilized. As indicated, tapes of different surface friction characteristics and different degrees of body may require alterations of the winding mechanism. With certain types of ribbon it may even be more desirable to utilize a revolving drum or other appropriate coiling or winding mechanism, all as is known to persons skilled in this art.

The tape material from which the base strips are cut should be fairly stiff and quite resilient so that it will open the hanks approximately to a position as indicated in FIG. 22 subsequent to being folded about the hanks for the stapling steps. This strip may also conveniently serve as an applicator for securing the resulting hank or the ultimate bow to a package as by utilizing a tape having a heavy paper backing with an adhesive mass on its exposed surface. The adhesive mass may be given interim protection by means of a removable paper cover sheet, in a well-known manner. An example of a suitable base strip-applicator tape is a pressure sensitive, protective covered tape product "Kleen-Stik" sold by Kleen-Stik Products, Inc., Chicago, Illinois.

In preparing the coil 166 and transferring it to the gripper mechanism, due regard should be had to positioning the ends of the ribbon of the coil so that these ends will ultimately extend beneath but terminate rather closely adjacent the superposed portions of the mounting strip. This eliminates the possibility of a single ribbon end extending among the formed loops of the resulting bow when the end loops of the hank are unnested, and thus assures a pleasing appearance of the resulting bow. In one model of the illustrated machine actually constructed, control of the ribbon feeding and metering mechanism was obtained by providing a four-way, solenoid actuated, spring return, lapped spool valve, sold under the designation of "Hi-Cyclic" by the Beckett-Harcum Company of Wilmington, Ohio, for valve 50. The solenoid of this valve was controlled by a counter-type timing mechanism 49 drive-connected to feed roller 43 by a timing belt as aforescribed. With this arrangement, the positioning of the ribbon ends was controlled within a tolerance of approximately one-half inch, which was found to be satisfactory.

It will be obvious that various modifications of the specific embodiment illustrated herein may be made in light of the above teachings, by those skilled in this art, without departing from the spirit and scope of this invention in its broader aspects. For example, different winding means may be utilized, different discharge means may be incorporated, various securing devices may be applied by different well-known securing mechanisms, various other movable support arrangements may be provided for the gripper mechanisms, and many other details of con-

struction may be altered within the scope of the invention herein. In addition, as regards the method, various steps may be carried out by hand or by other machines.

An illustrative hand-operated hank forming apparatus 5 incorporating the method disclosed and claimed herein, in its broader aspects, is disclosed in a copending patent application of the applicants herein, Serial No. 79,909, filed December 30, 1960.

It will thus be seen that a novel improved hank forming machine has been provided which illustrates and incorporates a novel, simple and expeditious method for forming hanks of ribbon particularly adapted for forming decorative bows, and which machine is capable of mechanically and automatically forming such hanks on an 15 economic, high volume production basis with a minimum of manual labor or personal attention to the machine.

It will be appreciated by those skilled in this art that the illustrated machine embodies a combination of operative mechanisms which cooperate to obtain the broader 20 object set forth herein and that other specific structural elements may be substituted for certain of the elements of this combination without departing from the spirit and scope of this invention. At the same time, it will also be appreciated that the disclosure teaches various improved subassemblies which are novel and embody inventive concepts, apart from the overall combination of elements. For instance, certain of the novel subassemblies 25 may advantageously be incorporated in hank forming operations wherein other steps, such as securing the base strip to the coil and/or discharging the bows, are manually 30 performed.

While particular embodiments of this invention are shown and/or described above, it will be understood, of course, that the invention is not to be limited thereto since 35 many modifications may be made by those skilled in the art in the light of the foregoing teachings. It is contemplated therefore by the appended claims to cover any such modifications as fall within the true spirit and scope of this invention.

We claim:

1. A machine adapted for forming a hank designed to 40 form a decorative bow comprising in combination anvil means, means for supporting a multilayer coil of ribbon encircling said anvil means, and a pair of securing means for applying separate securing devices to opposing side portions of such coil against said anvil means.

2. In a machine adapted for forming a hank designed 45 to form a decorative bow, anvil means, support means for holding a multilayer coil of ribbon with opposite side portions of the coil on opposite sides of said anvil means, means for placing a mounting strip with a portion adjacent each of such opposite side portions of said coil, and securing means for applying a separate securing device to the portion of the mounting strip and side portion of 50 the coil on each such opposite side of said anvil for independently securing said mounting strip to each such opposite side portion of such coil.

3. In a hank forming machine, winding means for 55 forming a length of ribbon into a composite coil of several contiguous layers of ribbon, a plurality of work supports mounted for movement to a plurality of predetermined positions including a first position adjacent said winding means, means for moving said work supports between said predetermined positions, each of said work supports including means for supporting a coil of ribbon 60 with two opposite portions of such coil in spaced adjacent relationship, means for transferring a coil from said winding means to one of said work supports in said first position, means adjacent a second of said predetermined positions for folding a flat resilient base strip onto such coil at such second position with opposite end portions of such strip overlying such opposite portions of the coil, and securing means for independently securing such opposite end portions of said base strip to the adjacent portions 65 of such coil on said supports.

4. In a hank forming machine as in claim 3 and including coil sizing means adjacent said second position and engageable within ribbon coils on said work supports for sizing the inner turns of a coil at said second position.

5. In a hank forming machine, winding means for forming a generally cylindrical coil of several coextensive contiguous layers of ribbon, a cantilever support and retractable gripping means engageable with opposite sides of said support spaced axially of a coil formed and supported by said winding means, said winding means being reciprocably mounted for movement to a position wherein such formed and supported coil surrounds said cantilever support, means for placing portions of said coil at opposite sides of said cantilever support between said support and said gripping means whereby said coil is gripped and held with opposite side portions independently supported, and securing means for securing the layers of each of said opposite portions together independently of such securing of the layers of the other of said opposite portions.

6. In a hank forming machine as in claim 5 and including applicator means for folding a base strip over said cantilever support and the gripped portions of such coil with opposite end portions of such strip overlying said opposite side portions of said coil, and wherein said securing means is adapted to secure opposite portions of such strip to said opposite portions of said coil.

7. In a hank forming machine, winding means for forming a generally cylindrical coil of several coextensive contiguous layers of ribbon, a cantilever support and retractable gripping means engageable with opposite sides of said support for supporting a coil of ribbon with two opposite portions thereof in spaced adjacent relationship, said support and gripping means being mounted for movement to a plurality of predetermined positions, means for moving said support and gripping means between said positions, means for transferring a coil from said winding means to said support and gripping means in a first of said positions, sizing means adjacent a second of said positions including a pair of pins reciprocably supported for movement into position within the end loops of a coil on said support and gripping means, means for reciprocating said pins and means for oscillating said pins mutually outwardly to size said coil, and securing means for securing the layers of such opposite portions of such coil together independently of such securing of the layers of the other of said opposite portions.

8. In a hank forming machine, a coil support mounted for movement between a plurality of predetermined positions and means for so moving said support, said support including a cantilever member and grippers engageable with opposite sides of said cantilever member for independently supporting opposite side portions of a coil, base strip applicator means disposed adjacent one of said positions; said applicator means comprising feed means for placing a base strip adjacent but transverse to the distal end of said cantilever member, reciprocable base strip applying means including a resiliently mounted abutment member for holding such base strip against the distal end of said cantilever member, a pair of spaced presser members resiliently biased toward one another and normally spaced apart a distance approximately the thickness of said cantilever member, and means for reciprocating said presser members to and from a position astraddle said cantilever member for folding such strip over such coil; and means for operating said grippers to engage and hold such base strip over such coil.

9. In a hank forming machine, a hollow cylindrical receptacle, feed means cooperating with said receptacle to form a hollow cylindrical coil of several coextensive contiguous layers of ribbon in said receptacle, a work support mounted for movement to a plurality of predetermined positions, means for moving said work support between said predetermined positions, said work support including a cantilever support member and retractable gripping means for holding opposite portions of a coil of

70 ribbon on opposite sides of said cantilever support, said cantilever support being in alignment with said receptacle when in a first of said positions, said receptacle being slidably mounted for movement to a position surrounding said

5 cantilever support, means for placing opposite side portions of such coil beneath said gripping means, coil sizing and base strip applicator means positioned adjacent a second of said predetermined positions and reciprocably mounted for movement into engagement with a coil held by said cantilever support and gripper means at said second position, means for reciprocating said sizing means, said sizing means including a pair of pins disposed to intersect the end loops of a coil at said second position, means for oscillating said pins mutually outward when engaged in such loops to size a coil; said applicator means comprising feed means for placing a base strip adjacent but transverse to the distal end of said cantilever support, a resiliently mounted abutment member for holding such base strip against the distal end of said cantilever member, 10 and a pair of spaced presser members resiliently biased toward one another and normally spaced apart a distance approximately the thickness of said cantilever member; means for reciprocating said presser members to and from a position astraddle said cantilever member for folding 15 such strip over such coil, and means for operating said grippers to engage and hold such base strip over such coil.

10. A hank forming machine comprising a hollow cylindrical ribbon receptacle having a peripheral ribbon receiving slot, intermittent movement ribbon metering feed means for feeding predetermined lengths of ribbon through said slot into said receptacle generally tangentially of the inner periphery of said receptacle, opposed coil collapsing fingers mounted for movement radially inwardly of said receptacle for collapsing a coil of ribbon therein to an oblong form, said receptacle and fingers being mounted for translational movement axially of said receptacle, a rotatable turret, a plurality of coil grippers mounted on said turret for movement to a plurality of predetermined positions including a first position in axial alignment with said receptacle, each of said grippers including a flat anvil and a pair of gripping fingers normally engaging said anvil on opposite sides thereof, spring means for biasing said fingers toward said anvil, means for selectively moving said fingers away from said anvil, hank sizing means and a mounting strip applicator adjacent a second of said predetermined positions, said applicator including a support slidably inwardly toward and outwardly away from a gripper in said second position, feed means actuated by movement of said support for feeding a predetermined length of a mounting strip transversely of the free edge of an anvil and supported hank in said second position, an abutment member slidably and yieldably mounted on said support in alignment with an anvil in said second position to abut such anvil upon inward movement of said support, clamp members mounted on said support on opposite sides of said abutment member and resiliently biased toward one another, said clamp members positioned to slide over an anvil in such second position, adjacent said grippers, on inward movement of said support, operating means for driving said grippers to receive and retain a mounting strip while said clamp members are extended inwardly, hank sizing fingers mounted on said support and positioned to enter each end of a hank supported on an anvil in such second position, a pair of staplers at a third of said positions disposed one on each side of an anvil in such position, said staplers positioned to apply separate staples to the portion of a mounting strip and ribbon on each side of an anvil in such position, hank discharge means at a fourth of such positions; and drive means for operating said ribbon feed means, said gripper fingers, said turret, said staplers and said discharge means, and for reciprocating said support and moving said fingers mutually outward for sizing coils.

11. A machine adapted for forming a hank designed to

form a decorative bow comprising in combination means for winding a length of ribbon into a composite open-centered coil of several coextensive, contiguous layers of ribbon, support means disposed in alignment with the open center of an annular coil supported by said winding means and engageable within such coil for maintaining opposite portions of such coil in spaced relation to one another, and means for applying a securing device through the contiguous layers of each such opposite portion of a coil so engaged on said support means independently of such application of a securing device to the contiguous layers of the other such opposite portion.

12. A machine adapted for forming a hank designed to form a decorative bow comprising in combination anvil means, a pair of spaced opposed securing means for applying securing devices against opposite sides of said anvil means, and means for supporting a multilayer coil of ribbon and positioning such coil around said anvil means with opposite side portions thereof between said anvil means and said opposed securing means, whereby separate securing devices may be independently applied to such opposite side portions of such coil and against said anvil means by said securing means.

13. A machine adapted for forming a hank designed to form a decorative bow comprising in combination means for winding a length of ribbon into a composite open-centered coil of several coextensive contiguous layers of ribbon, support means disposed in alignment with the open center of an annular coil supported by said winding means and engageable within such coil for maintaining opposite portions of such coil in spaced relation to one another, and means for simultaneously applying securing devices through the contiguous layers of each such opposite portion and against said support means.

14. A hank forming machine comprising in combination means for forming a length of ribbon into a composite coil of several contiguous layers of ribbon, such coil comprising two end portions and two spaced opposed side portions, support means engageable within a coil supported by said forming means and between said side portions for supporting said side portions in spaced relation to one another, means for applying a mounting strip to a coil on said support means with portions of such strip overlapping such side portions, means for applying a securing device through each such overlapping strip portion and the underlying contiguous layers of the respective side portion of a coil engaged on said support means independently of such application of a securing device to the other overlapping strip portion and respective underlying side portion.

15. A method of forming a hank adapted for forming into a decorative bow comprising winding a length of ribbon into a coil having a plurality of contiguous superimposed loops, said coil including two end loop portions and two opposing side portions having inner and outer surfaces, forming a mounting strip with opposite end por-

tions over the corresponding surfaces of said opposing side portions and with a portion of said strip extending between said surfaces at one edge of said coil, and separately securing each of said side portions to the adjacent portion of the mounting strip.

5 16. A method of forming a hank adapted for forming into a decorative bow comprising winding a length of ribbon into a coil having a plurality of contiguous superimposed loops, said coil including two end loop portions and two opposing side portions having inner and outer surfaces, forming a mounting strip with opposite end portions over corresponding surfaces of said opposing side portions and with a portion of said strip extending between such surfaces at one edge of said coil, separately securing each of said side portions to the adjacent end portion of the mounting strip, and spreading said mounting strip whereby said side portions are placed in generally parallel side-by-side relation.

10 17. A method of forming a bow comprising the steps recited in claim 16, and separating each loop of ribbon of said end loop portions from each other loop to form a decorative bow.

15 18. A method of forming a hank adapted for forming into a decorative bow comprising winding a length of ribbon into a multilayer coil; collapsing said coil to place two opposite side portions in closely spaced, generally parallel relation; positioning a base strip with one end portion thereof adjacent one of said opposite side portions and another end portion thereof adjacent the other of said opposite side portions, and with an intermediate portion joining said end portions at one edge of said hank; securing each of said end portions to the respective adjacent side portion and securing the layers of each such side portion together independently of such securing of the other 20 30 35 40 45 side portions and the other of said side portions, and substantially flattening said base strip to place said side portions in generally parallel side-by-side relation.

19. A method of forming a hank as in claim 18 and wherein the base strip positioning step comprises forming a resilient strip over one edge of such coil and over the outer surfaces of said side portions.

20. A method of forming a hank as in claim 18, and including a step of sizing the inner turns of said coil prior to securing the layers of said side portions together.
